UNITED STATES PATENT OFFICE.

EMIL G. SAUER, OF BROOKLYN, NEW YORK, ASSIGNOR TO THE LOWELL MANUFACTURING COMPANY, OF MASSACHUSETTS.

DESIGN FOR CARPET.

SPECIFICATION forming part of Design No. 24,729, dated October 1, 1895.

Application filed August 31, 1895. Serial No. 581,158. Term of patent 3½ years.

To all whom it may concern:

Be it known that I, EMIL G. SAUER, a citizen of the United States, and a resident of Brooklyn, in the county of Kings and State of New York, have invented a new and original Design for Carpets and Borders, known as "Pattern No. 4,775," of which the following is a specification.

This invention comprises two parts—namely, the design A for a carpet and the design B for a border; and I do hereby declare that the drawing accompanying this specification conveys to any one a clear understanding of the same and is sufficient to enable such a person to use my invention.

The design A is characterized by ornamented diamond-shaped figures and by escutcheon-shaped figures with connected bars at their sides constituting its leading features.

The design B is characterized by three ornamental bands, the inner one being characterized by ornamental diamond-shaped figures

and escutcheons, the second band being characterized by conventional Indian figures, and the third band being characterized by escutcheon-shaped figures in pyramidal arrangement, these, respectively, constituting its leading features.

What I claim, and desire to secure by Letters Patent, is—

1. In a design for a carpet, the body A, substantially as shown.
2. In a design for a carpet, the border B, substantially as shown.
3. The design for a carpet, comprising the body A and the border B, substantially as shown.

In testimony whereof I have signed my name to this specification in the presence of two subscribing witnesses.

EMIL G. SAUER.
